UNITED STATES PATENT OFFICE.

JOSEPH J. BODY AND MASON L. JOHNSON, OF DANTE, AND CHARLES F. KILGORE AND ALONZO BLEVINS, OF COEBURN, VIRGINIA, ASSIGNEES OF ONE-FIFTH TO LEE LONG, OF DANTE, VIRGINIA.

MINE-DOOR.

1,255,697.

Specification of Letters Patent.

Patented Feb. 5, 1918.

Application filed August 15, 1917. Serial No. 186,389.

To all whom it may concern:

Be it known that we, (1) JOSEPH J. BODY, (2) MASON L. JOHNSON, (3) CHARLES F. KILGORE, and (4) ALONZO BLEVINS, citizens of the United States, residing at (1 and 2) Dante, in the county of Russell, State of Virginia, and (3 and 4) Coeburn, in the county of Wise, State of Virginia, have invented certain new and useful Improvements in Mine-Doors; and we do declare the following to be a full, clear, and exact description of the invention, such as will enable others skilled in the art to which it appertains to make and use the same.

Our invention relates to improvements in mine doors and has for its object to provide a simply constructed and inexpensive door of this class which will be opened automatically by a car passing through the tunnel, the arrangement being such that the door will be opened in the direction in which the car is traveling, after which it will return to its closed position and be locked in this position.

With the foregoing general object in view, the invention resides in certain novel features of construction and unique combinations of parts to be hereinafter fully described and claimed, the descriptive matter being supplemented by the accompanying drawings which form a part of this specification and in which:

Figure 1 is a top plan view of the door operating mechanism;

Fig. 2 is a vertical transverse section on the plane of line 2—2 of Fig. 1;

Fig. 3 is a side elevation;

Fig. 4 is a longitudinal section on the plane of line 4—4 of Fig. 1;

Fig. 5 is a diagrammatic view similar to Fig. 4 showing the depressible rails forced downwardly by a car thereon to open the door;

Fig. 6 is a detail vertical section on the plane of the line 6—6 of Fig. 4;

Fig. 7 is a detail longitudinal section through one joint of the depressible rails;

Figs. 8 and 9 are detail longitudinal sections on the planes of the lines 8—8 and 9—9 of Fig. 1, respectively; and

Fig. 10 is a detail horizontal section on the plane indicated by the line 10—10 of Fig. 2.

In the drawings above briefly described, the numeral 1 has reference to a mine tun-

nel through which a railway track passes, said track including the usual rails 2. A door is provided across the track, said door including a pair of horizontal swinging sections 3 preferably formed of wooden frames 60 and metal panels 5 nailed thereto as shown in Fig. 10, so that the action of the air against these panels will not loosen the nails, regardless of the direction in which the door swings. On one side of the door, the space 65 between the latter and the wall of the tunnel is closed as shown at 6, whereas a man door 7 is provided at the opposite side so that the miners may pass through the tunnel without opening the door sections 3, 70 both of these sections being so located as to prevent opening thereof by any means other than a car passing along the track. Any suitable latch such as that indicated at 8 may be provided for holding the door 7 in 75 closed position and this door will in most cases be provided with spring hinges 9.

The door sections 3 are rigidly secured to vertical rock shafts 10 whose lower ends carry pinions 11 meshing with gears 12, the latter in turn meshing with the teeth of a pair of longitudinal rack bars 13 which are received slidably in channel bars 14 anchored to one of the ties of the track and extending longitudinally of the latter. Roller 85 bearings 15 are preferably provided for facilitating movement of the rack bars.

Vertical lugs 16 rise from the rack bars 13 and are apertured to receive a pair of longitudinal rods 17 which are adjustably secured thereto by nuts 18, the outer ends of said rods having horizontal arms 19 held adjustably thereon by additional nuts 20. The arms 19 extend toward the rails 2 and are adjustably connected by nuts or the like 21 95 with additional longitudinal rods 22, the outer ends of said rods 22 being pivoted to vertical crank arms 23 on a pair of transverse rock shafts 24 which extend beneath the rails 2 at longitudinally spaced points. 100

Each rock shaft 24 is provided with a pair of inclined crank arms 25, the arms of one shaft being inclined oppositely from those of the other and all of said arms being set at approximately 45° to the horizontal. Links 26 rise from the crank arms 25 and are pivoted to the lower ends of lugs 27 which depend from the ends of a pair of depressible rails 28, said rails being tied together by bridle bars 29. At 30, a pair of 110

rail points 31 are loosely connected to the ends of the rails 28, the outer ends of said points resting on suitable bars or the like 32 and being loosely held in place by suitable 5 fastenings 33. Coiled springs 34 are positioned beneath the centers of the rails 28 for normally raising them above the rails 2, and by preference pins 35 depend from said rails through said springs and into sockets 10 36 formed in one of the ties of the track.

A pair of depressible latch members 37 are provided for normally locking the doors 3 in closed position, said members having central notches 38 to receive lateral arms 39 on the 15 lower ends of the shafts 10, when the doors are closed by means of suitable springs 40, said springs being mounted on bolts 41 beneath the rods 22 and connected with said rods by arms 42 which depend therefrom. 20 Suitable guides 43 are provided for bolts 41, and it is between these guides and the arms 42 that the springs 40 are located. By this arrangement, whenever the operating mechanism of the door is actuated by the passage 25 of a car over rails 28, the several parts will be automatically returned to their initial position when the car travels from said rails.

For the purpose of releasing the latch member 37 to permit the door to open, longitudinal rock shafts 44 are mounted between the rails 2, one end of said shafts having crank arms 45 operatively connected with the ends of said members 37, whereas the other ends of said shafts are equipped 35 with additional crank arms 46 received in forks 47 which depend from the rail points 31. (See more particularly Fig. 4).

The springs 48 beneath the latch members 37, normally raise said members to operative position, but the passage of a car upon the rail points 31 from either direction, will depress the arms 46 so that the rock shafts 44 are operated to lower said latch members, thus releasing the arms 39. As the 45 rails 28 are now depressed, the arms 25 nearest the approaching car, are forced downwardly to the position of Fig. 5, whereas the other arms will move upwardly to the vertical position shown in this figure. In moving upwardly in this manner, the last named arms will of course raise one end of the rails 28 until said arms and the links 26 connected thereto, move beyond dead center, but the depressible rails 28 are sufficiently 55 springy to permit this movement without in any manner impairing the operation of the device.

Actuation of the crank arms 25 as above described, will so turn the rock shafts 24 as 60 to cause the parts 23, 22, 19, 17, 13, 12 and 11 to swing the door sections 3 open in the direction in which the car is traveling. This action will take place whether the car be moving in one direction or the other, and the 65 moment said car leaves the depressible rails,

the several springs above described will return all parts to their initial position.

From the foregoing, taken in connection with the accompanying drawings, it will be obvious that although the device is of comparatively simple and inexpensive construction, it will be highly efficient and durable. Since probably the best results are obtained from the specific details shown and described these details constitute the preferred form of 75 the improved door, but we wish it understood that within the scope of the invention as claimed, numerous minor changes may well be made without sacrificing the principal advantages. 80

In conclusion, it may be stated that the invention has been in every day use in a coal mine for several months and has been found to operate perfectly under all conditions encountered. 85

We claim;

1. The combination of a door to extend across a roadway, a depressible member adapted to extend longitudinally of the roadway, a pair of rock shafts extending 90 transversely beneath the ends of said member, means for operatively connecting said shafts to the door for opening the latter in one direction when said shafts are turned clockwise and for opening it in the other direction when said shafts are moved counterclockwise, a crank arm on each shaft, and links rising from said arms to said depressible member and pivoted to both, said arms being parallel to said depressible member 100 and inclining in different directions.

2. The combination of a swinging door adapted to extend across a roadway, a depressible member beneath said door and adapted to extend longitudinally of the 105 roadway, a channel bar adapted to be anchored at a point spaced outwardly from the roadway, said channel bar extending parallel with said depressible member and having one of its side flanges formed with 110 a longitudinal slot, a rack bar slidably received in said channel bar, operating connections between said rack bar and said door including a gear extending through said slot and meshing with said rack bar, and operating connections between said rack bar and said depressible member. 115

3. The combination of a swinging door adapted to extend across a roadway, a depressible member beneath said door and adapted to extend longitudinally of the roadway, a longitudinally slid able operating member spaced outwardly from and parallel with said depressible member, operating connections between said operating member and the door, arms extending toward said depressible member from the ends of said operating member, a pair of longitudinal rods to which said arms are secured, rock shafts extending transversely beneath said depressible member. 120

ble member and operatively associated with the latter and with said rods, additional arms depending from said rods and having longitudinal bolts on their lower ends, slides 5 in which said bolts are slidably received, and springs on said bolts for returning them to their initial positions after shifting thereof.

4. The combination of a swinging door adapted to extend across a roadway, a depressible member extending beneath said door and adapted to extend longitudinally of the roadway, operating connections between said member and said door, a depressible latch member for holding the door in 15 closed position, a rock shaft substantially

parallel with said depressible member, a crank arm on one end of said shaft operatively associated with said depressible member, and a second arm on the other end of said shaft for depressing said latch member. 20

In testimony whereof we have hereunto set our hands in the presence of two subscribing witnesses.
